Inventor:

William H. Paige

Br. Geol. W. T. Hibbitts, A.M.

UNITED STATES PATENT OFFICE.

WILLIAM H. PAIGE, OF CLEVELAND, OHIO.

RAILWAY PASSENGER-CAR.

SPECIFICATION forming part of Letters Patent No. 291,622, dated January 8, 1884.

Application filed August 29, 1883. (No model.)

To all whom it may concern:

Be it known that I, WILLIAM H. PAIGE, of Cleveland, in the county of Cuyahoga and State of Ohio, have invented certain new and 5 useful Improvements in Railway Passenger-Cars, of which the following is a specification.

My improvements relate to the peculiar construction, with paper and iron, of passenger-cars, as hereinafter described and claimed.

10 In the accompanying drawings, Figure 1 is a side elevation of a passenger-car embodying my improvements, showing parts broken away to better illustrate the interior construction. Fig. 2 is an end elevation, showing one-half of 15 outside and one-half of inside finish. Fig. 3 is a floor plan, showing arrangement of seats and aisles. Fig. 4 shows arrangement of sills. Fig. 5 is an enlarged vertical section of side wall of car, showing arrangement of window-sash and panels. Fig. 6 is an enlarged sectional view of one of the side posts, showing arrangement of window-sill and method of 20 constructing side of car. Fig. 7 is an enlarged horizontal section of a post, showing arrangement of sash and panel therewith. Fig. 8 shows form of carlines in constructing the roof and method of attaching same to the 25 side walls of the car.

A A in the several figures are the sills for 30 the foundation, and consist of angle and T-iron, the two side sills being of angle and the interior ones being of T-rails. The two side rails are filled with wood, and one side of the T-rails is filled with wood, firmly bolted together, thus forming the support for the 35 flooring of the car. The two side rails are made shorter than the interior rails, which, extending beyond the ends of the car, form the supports for the end platforms.

40 B B are T-iron posts, set in pairs, having a portion of the web cut out so as to fit them to the side rails, A, to which they are secured by bolts or screws.

B' B' B' are flanges on the post B. The 45 flanges B' B' secure the sash, and B' secures the side paneling. The wide spaces between said posts are intended for windows, while the narrow spaces are closed with paper panels. The tops of said posts are secured to an iron 50 cap-rail, C. A flat iron bar, D, is secured on the outside of said posts on a line with the bottom of the window-openings. The cap C

and the bar D secure all the posts together, and the said posts are also braced on the inside below the window-openings by cross-bar braces d d. This completes the side framework of the car. The spaces below the windows are filled with paper panels, which, as well as the long narrow panels, are secured in place by rivets, as seen at r, Figs. 5, 6, and 7. The paper employed is thick, heavily-prepared 55 paper for this purpose.

The window-sills consist of sheet metal, formed as seen at S, Figs. 5 and 6, and are secured to the posts by rivets s s, the outside 60 edge of said sill lapping over the edge of the bar D. Above the window-openings is placed a lettering-plate of paper, over the top edge of which the lower edge of the cap-piece C lies, and the spaces between the flanges of the 65 posts are filled in with paper pieces, giving a neat and strong finish to the outside above the windows. The sash for the windows rest against the flanges B' B' of the posts, as seen in Fig. 7, and slide between said flange and a 70 stop, t, secured to the web of the post. The ends of the car are made like the sides, with posts set up in like manner, the corners being made with a quarter-bent panel secured to two 75 posts like the other panels. The corner panels are further supported by a wooden post, p, fitted into the hollow of the panel and secured between the two posts, as seen in Fig. 80. 3. The door-posts are constructed in like manner to the said corners, and by this arrangement the doorways are wider than usual, and are closed by double sliding doors, making the ingress and egress to the car more 85 convenient. In the plan shown in Fig. 3 the seats are arranged in the central part of the car, 90 with an aisle on each side, thereby greatly increasing the seating capacity over the side-seat plan. A sash-partition, K, is placed at each end of the row of seats opposite the doorways, which serve to break the currents of 95 air when the car is in motion and the doors are open.

The roof is constructed of the same material as the body.

The carlines F are formed of the T-iron, as 100 represented in Fig. 8, and are secured to the plate C, the web of the carline being cut away to fit over a wooden filling-plate, C, the outer edge of which forms a molding under the eaves

of the roof. Over the said carlines is placed a paper roofing, the lower edge of which is turned down over the edge of said molding. The dome of the roof is provided with 5 venti-lating-windows, in similar manner to other cars now in use.

The paper paneling is capable of being painted and highly finished, and in my construction the said panels are finished on both 10 the outside and inside alike, so that linings or ceilings other than these panels are unnecessary, thus rendering the car lighter in weight and appearance.

Having described my invention, I claim—
15 1. The combination, in a car constructed of iron and paper, of the wooden filling in the corners, and door-posts of a car, substantially as specified.

2. The arrangement of a central row of reversible back seats, and the partitions K with 20 side aisles in a car, as shown and described.

3. The T-iron posts B B, side rails, A, cap-rail C, bar D, and cross-braces d, substantially as described, and for the purposes set forth.

4. The T-iron posts B B, side rails, A, cap-rail C, bar D, and cross-braces d, the space 25 below the window being filled with paper panels, all united and secured in the manner specified.

5. In a car, the seats placed transversely in 30 the center thereof, whereby two side aisles are formed, in combination with the sash-partition K, as specified.

6. A railway-car the outer and inner paneling whereof are made of paper, substantially 35 as set forth.

WILLIAM H. PAIGE.
